UNITED STATES PATENT OFFICE.

WILLIAM A. GILDAY, OF PHILADELPHIA, PENNSYLVANIA.

ANTISUBMARINE.

1,267,539.

Specification of Letters Patent. Patented May 28, 1918.

Application filed September 7, 1917. Serial No. 190,153.

To all whom it may concern:

Be it known that I, WILLIAM A. GILDAY, a citizen of the United States, residing at Philadelphia, in the county of Philadelphia and State of Pennsylvania, have invented 5 certain new and useful Improvements in Antisubmarines, of which the following is a specification.

This invention relates to protective and 10 offensive devices and particularly to that class, which is designed to be applied to vessels, to protect them from damage of any sort to their hulls and especially such damage as arises from the explosion of mines, torpe- 15 does, and the like, near or adjacent thereto.

A further object of the invention is to pro- 20 vide a device of this character which will offer the least possible impedance to the speed of the ship to which it is applied.

And another object is to provide a series 25 of plates forming an auxiliary or secondary outer side of the hull of a vessel and so connected thereto that said plates can be folded or otherwise brought into close proximity 30 to the sides and hull of a vessel either in unison or independently of one another.

A still further object of the invention com- 35 prises the combination of a plate pivotally secured to the outer side of the hull of a vessel and adapted to be swung into close proximity thereto when its function is not needed, with a plate yieldingly secured to the bottom of the vessel and operative to yield upwardly upon striking a submerged object.

And a still further object is to provide a 40 suitable means for actuating the auxiliary hull sections or armor plates above referred to, either singly or in groups.

And yet another object of the invention 45 resides in the formation or provision of an improved form of open lattice work or gratings positioned opposite to, and operative to protect, the tapering bow section of the vessel and at the same time to offer a minimum retardation to the speed of said vessel as said gratings encounter the water resistance caused by the forward motion of the vessel.

Further objects and advantages in the in- 50 vention, together with the various details in the construction and operation of the pre- 55 ferred form of the device are fully described in the following specification when read in conjunction with the accompanying drawings, in which Figure 1 is a side elevation of a vessel equipped with the improved de- 60 vice; Fig. 2 is a top plan view of the same;

Fig. 3 is a vertical, transverse section through the vessel; Fig. 4 is an enlarged detailed sectional view of the left hand side of Fig. 3; Fig. 5 is a detailed view of one of the hinged pins for the side sections; Fig. 6 is an enlarged fragmentary detailed section illustrating the coöperation of said sections; Fig. 7 is an enlarged fragmentary view of the keel member; Fig. 8 is an enlarged detailed view of the adjacent portions of two of the bow gratings, and Fig. 9 is a vertical transverse section of the same.

Referring to the drawings a ship is represented as comprising a hull having vertical 70 side walls 1, and a substantially horizontally extending bottom wall 2 with the usual deck 3, super-structure 4, stacks 5, and loading derricks 6, while the bow of said hull is tapered forwardly in the usual manner as 75 shown in Fig. 2 and at the rear is tapered slightly and externally provided with additional armor protection in the form of plates 7, while a ram 8 extends longitudinally of and centrally beneath the bottom 80 wall 2 and at the same time comprises a means for cutting into a hollow body such as a submarine or the like.

Said bottom wall, in addition to being 85 protected by armor plates secured directly thereto, or by increasing the thickness of the wall, is protected by means of a series of oppositely extending metal plates 12, pivotally connected at 13 at opposite sides of said bottom wall and operative to yield upwardly 90 upon striking a submerged object or upon being struck by an exploding mine, torpedo, or the like, each of said plates being pro- 95 vided at its free edge portion with reduced tongue portions 14 extending slidably through, and operative to move upwardly in the corresponding apertures 15 in the ram 8, said apertures being thus shown in Fig. 7. The tongues of the plates extending in one direction are arranged out of alinement 100 with the tongues of the plates extending in an opposite direction, so that the movement of none conflicts with the position or move- 105 ment of any of the others.

Extending in substantially parallel rela- 110 tion with the opposite sides of the ship's hull and between the tapered bow and stern por- tions is a series of armor plates 20, the for- ward plate of each consecutive pair over- laps the next plate rearwardly thereof as shown in Fig. 6, while the former is pro- 115 vided with a plurality of dowel pins 21,

adapted to enter the recesses 22 in an oppositely positioned portion of the latter, and operative thereby to prevent a shifting of one plate with respect to the next adjacent thereto in their common plane, while in either a raised position against, or when spaced angularly away from, the said sides of the ship's hull. Each of these plates is preferably laminated or at least of double thickness in order to make the same relatively flexible and less likely to become destroyed or cracked upon being struck by an exploding mine or submarine against which they are designed to protect the ship by which they are carried.

Referring particularly to Fig. 4, the plates 20 are provided with lugs 21^a, which are so curved as to fit snugly into hollowed brackets 22^a, secured to the opposite lower portions of the side walls of the ship's hull, said lugs being removably retained in position within said brackets by means of a pin (Fig. 5) provided with a shank 23, handle 24, and lug 25, said lug being adapted to pass through the transversely enlarged openings 26 in the sides of said brackets 22, and upon turning the shank by means of the handle attached thereto, to oscillate into such a position as to prevent any possible accidental removing of said pin from said bracket in which position the coöperation of the lug 21^a, bracket 22^a, pin 23 operate to form a rigid hinged mounting for each of the plates 20.

To predetermine and yieldingly maintain a definite position of said plates either singly or as a unitary wall with respect to the adjacent side walls of the ship's hull, there are provided links 30, secured by means of staples 31 to each of the said plates, while the innermost ends of said links slidably coöperate with the elongated staples 32. These links may be of any desired number and arrangement, while the plates which they are designed to position are reinforced longitudinally by means of angle bars 33 and of any desired number and position.

For raising and lowering the said protective plates 20 either singly or upon each side of the ship simultaneously, there is provided an individual motor 35 for each plate, preferably connected through an idler 36 to drive the drum 37, about which is coiled the intermediate portion of a cable or chain 38, the opposite ends 39 of which extend respectively upwardly and downwardly and over pulleys 40, supported by a suitable frame 41 provided with spaced apertures 41^a, and are secured at their ends to a sliding block 42, provided with a hole 42^a and a lug 43 to which is pivotably secured a link 44, which at its opposite end is pivotably secured by means of an eyelet staple 45 to the uppermost edge portion of its adjacent plate 20. The operating motor idler and drum are

preferably housed within a casing 46 and are so controlled as to be operated either individually or in groups as may be desired.

In operation the motor 35 raises the block 42 by means of the cable 38 and thus raises the rod 44 and the plate 20 to which it is secured, while with this action the upper links 30 at their inner ends slide along the staples 32 and take positions parallel with the adjacent side of the hull 1, and the lower links collapse, thus permitting the plate 20 to swing as a whole about the pin 23 in a position adjacent to and parallel with the side of the ship's hull. The rod 44, in addition to being employed as a means for raising the side plates 20, operates to maintain the respective plates to which each of said rods is connected in any one of said predetermined positions by raising or lowering block 42 until the aperture therein registers with any desired one of the series of holes 41^a in the post with guide 41, in which position said block and, consequently, the rod 44 and plates 20, connected therewith, are maintained by a pin passing through said registering apertures and hole.

As a continuation of the solid plate 20 to and around the tapered bow portion of the ship's hull would obviously offer too great a resistance to the passage of the water thereby there is provided over this portion and upon opposite sides thereof series of armor units 50, comprising a lattice work of horizontally extending angle irons 51 and vertically extending plates or rods 52, the downwardly extending flanges of the former being mutilated or entirely removed between the latter, to further decrease the resistance to the water offered thereby, the vertical plates adjacent to the units 50 being made to overlap and if desired provided with dowel pins or other locking means as previously described in connection with the side plates 20, said lattice work being pivotably connected to the hull of the ship in the same general manner as also previously described in detail, while the forwardmost lattice frame is pivotably mounted directly upon the upwardly extending prow 8^a. These units may likewise be raised and lowered either singly or in groups toward or away from the ship's side and in their outermost positions are yieldingly maintained in spaced relation from the ship's hull by means of the usual links 30 with their staple connections.

In view of the foregoing description and especially as illustrated by the accompanying drawings, it is obvious that there has been provided a protective means for the hull of a ship, which will offer a minimum degree of retardation against the surrounding water and in addition thereto presents certain features which are of especial advantage. It will be realized from examin-

ing the Fig. 3 in particular, that a torpedo or mine exploding beneath the ship's hull will have the major portion of its explosive force taken up by the yielding plates 12 and consequently lessen to a great degree the effective force of the explosion upon the bottom wall of the said hull. In addition to this the formation of the ram offers a means for cutting into a hull body such as 10 is presented by the construction of a submarine.

The operation of the invention in protecting a ship is similarly apparent from an understanding of the construction and 15 operation of the auxiliary, normally angularly disposed sides comprising a series of independently movable plates. In the event of a submarine striking one or more of these plates, the latter would readily 20 yield inwardly and the water between it and the hull would naturally be forced upwardly, thus absorbing a great amount of the shock of the explosion and transmitting but a small portion thereof to the 25 actual side of the hull proper. In addition to these advantages, the simple means for raising the auxiliary sides makes it possible for the same to be withdrawn into positions closely adjacent to the hull when 30 not in use and thus offering but very slight resistance to the buoying medium.

Having thus described my invention, what I claim and desire to protect by Letters Patent of the United States is:

35 1. A protective device, comprising the combination of a plate pivotably mounted upon the side of the hull of a vessel, means to yieldingly maintain said plate in angular relation or parallel with said side, a 40 second plate pivotably mounted to the underside of the said hull, keel provided with apertures and means carried by said second plate and extending into said apertures to limit downward movement of said second 45 plate with respect to said hull.

2. A protective device, comprising the combination of a series of overlapping plates upon the opposite sides of the hull of a vessel, means to yieldingly position the 50 individual plates of each series in spaced relation or parallel with the respective adjacent sides of said hull, an apertured keel carried by the bottom of said hull plates pivotably mounted upon said bottom and 55 means carried by said last-named plates and coöperating with the sides of said apertures to limit the downward movement of said second plates, all of said plates when in an operative position being adapted 60 to yield upon receiving an external impact.

3. A protective device, comprising a lattice work pivotably connected to the side of the hull of a vessel, means to yieldingly 65 maintain said lattice in operative extended

angular relation with said side, said lattice comprising horizontally extending angle irons and transversely extending bars connecting the same, the flanges of said angle irons lying in a plane with said lattice being 70 mutilated or entirely removed between said bars.

4. A protective device, comprising the combination of a plate pivotably mounted upon the side of the hull of a vessel, means to yieldingly maintain said plate in angular relation or parallel with said side, a second plate pivotably mounted to the underside of the said hull, keel provided with apertures, means carried by said second plate 80 and extending into said apertures to limit downward movement of said second plate with respect to said hull, and a lattice work section pivotably carried by the tapered bow portion of said side, and comprising longitudinal angle irons and transversely extending bars, the flange of said angle irons lying in the plane of said lattice work being removed from between said bars. 85

5. A protective device, comprising the combination of a series of overlapping plates upon the opposite sides of the hull of a vessel, means to yieldingly position the individual plates of each series in spaced relation or parallel with the respective adjacent sides of said hull, an apertured keel carried by the bottom of said hull, plates pivotably mounted upon said bottom and means carried by said last-named plates, coöperating with the sides of said apertures 100 to limit the downward movement of said second plates, all of said plates when in an operative position being adapted to yield upon receiving an external impact, and a series of overlapping lattice work frames 105 pivotably carried upon the opposite sides of said vessel and opposite to the tapered bow portion of the latter, said frames when in operative extending positions forming continuations of said series of plates, each 110 of said frames comprising longitudinal angle irons and transverse bars connecting the same, the flanges of said angle irons lying in a plane of said frame being removed from between said bars. 115

6. An apparatus for protecting ships against exterior harmful agencies, comprising a series of protecting members pivotably connected at their lowermost portions to the said ship adjacent to the bottom thereof, 120 and means for oscillating the said members toward or away from the sides of the ship, said means including guides upon the ship, members movable along said guides, and members pivotably connected to said last-named members and said first named members. 125

7. An apparatus for protecting ships against exterior harmful agencies, comprising a series of protecting members pivotably 130

connected at their lowermost portions to the said ship adjacent to the bottom thereof, and means for oscillating the said members toward or away from the sides of the ship, 5 said means including guides upon the ship, members movable along said guides, and members pivotably connected to said last-named members and said first named members, and braces pivotably connected to said 10 first members and slidably connected to the side of the ship.

8. An apparatus for protecting ships against exterior harmful agencies, comprising a series of protecting members pivotably 15 connected at their lowermost portion to the

ship adjacent to the bottom thereof, braces pivotably connected to said first members and slidably connected to the sides of the ship, and means for oscillating the said members toward or away from the sides of the ship, 20 said means including guides upon the ship, members movable along said guides, actuating means carried by said ship and operative to actuate said last-named members along said guides, and members pivotably 25 connected to said movable members and to said protecting members.

In testimony whereof I have affixed my signature.

WM. A. GILDAY.
